UNITED STATES PATENT OFFICE.

WILLIAM J. WOLFF, OF NEW YORK, N. Y., ASSIGNOR TO MEYER ROTHS-
CHILD AND RICHARD KUNO, OF NEW YORK, N. Y.

DESIGN FOR A BUTTON.

No. 88,135.

Specification for Design.

Patented July 31, 1906.

Application filed June 15, 1906. Serial No. 321,946. Term of patent 3½ years.

To all whom it may concern:

Be it known that I, WILLIAM J. WOLFF, a citizen of the United States, residing in New York, in the borough of Brooklyn, county of Kings, and State of New York, have invented a new, original, and ornamental Design for Buttons, of which the following is a specification, reference being had to the accompanying drawing, forming part thereof.

I claim—
The ornamental design for a button, as shown.

WM. J. WOLFF.
